UNITED STATES PATENT OFFICE.

WILLIAM L. VANCE, OF CHICAGO, ILLINOIS.

GAME.

1,296,882.

Specification of Letters Patent. Patented Mar. 11, 1919.

Application filed May 28, 1917. Serial No. 171,451.

To all whom it may concern:

Be it known that I, WILLIAM L. VANCE, a citizen of the United States, residing at Chicago, in the county of Cook and State 5 of Illinois, have invented certain new and useful Improvements in Games, of which the following is a description.

My invention belongs to that general class of miniature games designed to imitate as 10 near as may be on a limited scale the general plan of some popular game, and in the present instance to so imitate the game of baseball. It is particularly designed to make possible that desirable combination of skill 15 in the player and accident or chance present in all popular games, which holds the interest and adds fascination to the game. To this end my invention consists in the novel construction, arrangement and combination 20 of parts herein shown and described, and more particularly pointed out in the claims.

In the drawings, wherein like reference characters indicate like or corresponding parts,

25 Fig. 1 is a perspective view of the field; Fig. 2 is a plan view of the same; Fig. 3 is a sectional view on line 3—3 of Fig. 2; Fig. 4 is a similar view on line 4—4 of 30 Fig. 2, and Fig. 5 represents a player, for example one of the outfielders.

As shown in the drawings, the field or board is preferably sectional for convenience in handling, comprising sections 1, 2, 35 3, 4 and 5, suitably connected together by detachable means as 6, 7, 8, 9, 10, 11 and 12, or equivalent members. The field in general represents a base ball diamond, preferably inclosed except at the plate, and 40 catcher's station with a raised inclosing wall 13 to practically limit the movement of the ball to the field, and for other reasons hereafter mentioned. Within the part 1 a diamond is laid out with bases 14, and running 45 lines 15 thereon, 16 is the plate. The diamond is inclosed by a raised wall or obstruction 17, with three or more openings therethrough, communicating with the out-field, as at 18, 19 and 20. These openings 50 are of sufficient size to permit the ball to pass readily therethrough without touching the sides. The width of the openings, in one respect, determine the difficulties of 55 the game.

On or near the three distant sides of the

outfield inclosure 13 are positioned preferably rectangular traps 21, provided with flaps 22, or equivalent parts, permitting the ball upon striking the flaps to pass into the 60 trap, and tending to retain it therein. On or near the two side inclosures 13 adjacent to the plate, are preferably triangular traps 23, as shown, with similar flaps or equivalent parts 24.

The triangular stations from 25 to 33 inclusive form obstructions, and indicate the suggested positions of the players in the field. These may be adjustable as to position, if desired, and are constructed to support in an upright position figures of the 70 players as 34. The players may be represented in different attitudes.

The manner of delivery of the ball to the batter is of importance to create and maintain interest in the game. In the preferred means shown in the drawings, a concave trough 35 is supported in an inclined position, as indicated by any preferred means. As shown a wire support 36 supports the 80 rear of the trough, while a support 37 supports the forward end preferably at a point near the pitcher's station. Any preferred means may be employed to retain the trough against end movement. As shown an extension 38 on the support 36 extends through an opening in the trough for this purpose. It will be noted that the supports for the trough are so positioned as not to interfere with the movement of the ball. 39 is a small 90 manually operated bat of any preferred form or size.

Practical operation proves that by a slight manipulation of the ball at the instant of delivery, the ball may be caused to 95 incurve or outcurve, may be slow or fast, and may possibly cause other movements baffling to the batter.

Suitable small disks may represent the 100 runners and their position on the bases.

Rules for playing the game and securing great enjoyment from it will occur to any one familiar with the game of baseball, and these may be varied as desired. I have created great interest among players by following substantially the following rules:

Rule 1: A ball striking any one player causes batter to be out.

Rule 2: A ball striking any three infielders causes three foremost runners to be out, 110 including batter as a runner.

Rule 3: A ball striking any two infielders

causes two foremost runners to be out, including batter as a runner.

Rule 4: When only one runner is on either 2nd or 3rd base, the above rule (Rule 3) does not apply, and only batter is called out.

Rule 5: A ball driven into the infield without striking a player is a one-base hit; batter advances to 1st base.

10 Rule 6: A ball striking the infield cushion and rolling to the outfield is counted for an outfield hit;

15 Rule 7: A ball driven into the outfield without striking a player is called a two-base hit; batter advances two bases;

Rule 8: A ball driven into any one of the three rectangular catches is called a three-base hit; batter advances three bases;

20 Rule 9: A ball driven into the triangular catches is a home run;

Rule 10: Runs are made by runners advancing the same as the batter;

Rule 11: With the exception of Rule 6 balls must be counted for whatever they directly strike;

25 Rule 12: A ball driven outside entire field is void.

Having thus described my invention, it is obvious that various immaterial modifications may be made in the same without departing from the spirit of my invention; hence I do not wish to be understood as limiting myself to the exact form, construction, arrangement and combination of parts 35 herein shown and described, and uses mentioned.

What I claim as new and desire to secure by Letters Patent is:—

1. In a game of the character described, 40 a field provided with a wall substantially inclosing the same, a second wall partially dividing the infield from the outfield, said second wall having an opening for the passage of a ball from the infield to the outfield in 45 combination with a guiding trough arranged to direct a ball toward the plate and deliver the same in the field at a point near the

pitcher's station, said trough being provided with an opening, and means for supporting the trough above the field, said means comprising a substantially U-shaped frame mounted at opposite sides upon said second wall at the sides of the opening therein, said frame having a portion at the top upon which the trough is adapted to rest, and also having a portion extending through the opening in the trough and serving to prevent endwise movement of the same, substantially as described.

2. In a game of the character described, 60 a field provided with a wall substantially inclosing the same, a second wall dividing the infield from the outfield and provided with an opening at second base for the passage of a ball from the infield to the outfield, an obstruction in the infield adjacent the pitcher's station, in combination with a guiding trough arranged to direct a ball toward the plate and deliver the same in the field at a point near the pitcher's station, said trough 70 having an opening near one end thereof, and means for supporting the trough at an inclination above the field; said means comprising a frame extending upwardly from said obstruction and upon which one end of 75 the trough is adapted to rest, and a substantially U-shaped frame of greater height than the first mentioned frame, the sides of said U-shaped frame extending upwardly from said second wall at opposite sides of 80 the opening therein, said last mentioned frame having portions at its top at opposite sides upon which the other end of the trough is adapted to rest, and an intermediate portion engaging the opening in the trough to 85 prevent lengthwise movement of the trough, substantially as described.

In testimony whereof I have hereunto signed my name in the presence of two subscribing witnesses.

WILLIAM L. VANCE.
